EXPANSIBLE HOUSE TRAILER

Clyde F. Wait and Donald F. Cole, Flint, Mich., assignors to Palace Corporation, Flint, Mich., a corporation of Michigan

Application April 15, 1954, Serial No. 30,040

Term of patent 14 years

(Cl. D14—3)

Des. 176,166

Figure 1 is an end view of an expandable house trailer embodying our new design, showing the trailer in expanded position.

We claim:

The ornamental design for an expandable house trailer, substantially as shown.
